UNITED STATES PATENT OFFICE.

JOSEPH M. SCHUTZ, OF MINNEAPOLIS, MINNESOTA, ASSIGNOR TO SCHUTZ-O'NEILL COMPANY, OF MINNEAPOLIS, MINNESOTA, A CORPORATION OF MINNESOTA.

DISINTEGRATOR.

SPECIFICATION forming part of Letters Patent No. 739,227, dated September 15, 1903.

Application filed May 10, 1900. Serial No. 16,114. (No model.)

To all whom it may concern:

Be it known that I, JOSEPH M. SCHUTZ, of the city of Minneapolis, county of Hennepin, State of Minnesota, have invented certain new and useful Improvements in Disintegrators, of which the following is a specification.

This invention relates to disintegrating or grinding machinery; and the object of my invention is to provide a disintegrator or grinding-machine that may be used in the pulverization of almost any material and which will also possess the qualities of a grader or separating-machine.

A particular object of my invention is to provide a disintegrator of an extremely simple and cheap construction and comprising parts that may be changed or repaired with the greatest ease and lowest possible expense.

A further and particular end in view in my invention demands the provision of a machine which will rarely clog regardless of the nature of the material that is being worked and which it will be practically impossible to break.

My invention consists generally in the combination with a substantially annular housing or casing or frame of an annular grinding-surface therein provided with longitudinal slots or spaces throughout its circumference and a revolving beater therein.

The invention further consists in a beater of peculiar construction and in various details included in the machine as a whole and in combinations of parts, all as hereinafter described, and particularly pointed out in the claims.

The invention will be more readily understood by reference to the accompanying drawings, in which—

Figure 1 is a perspective view of a disintegrator embodying my invention, the same being shown in connection with a novel means of collecting the products. Fig. 2 is a longitudinal vertical section of the disintegrator. Fig. 3 is a transverse vertical section on the line $x-x$ of Fig. 2. Fig. 4 is a perspective detail of the grinding-shell and parts of the beater. Fig. 5 is a detail of one of the beater-heads.

As shown in the drawings, my machine com-

prises two main parts—the disintegrator, in which the material is pulverized and wherein air is used in the process of grading or separating, and the collector, wherein the product of the disintegrator is deposited and the air-pressure is relieved. I will first describe the disintegrator. This comprises the heavy base 2, having the bearings 3 for the beater-shaft 4, the beater upon the end of said shaft, and the casing or housing 5, surrounding the beater and containing the grinding-shell 6. The casing or housing 5 is semicircular at the top, while its sides 5' extend in straight lines to the surface on which the machine rests. Both the back and the front of the casing or housing extend to the base plane, and the back is perforated only to receive the end of the shaft 4. The front of the casing is provided with a large central opening, and this is closed and the casing completed by the face-plate or disk 7, that contains the spout-like hopper 8. The spout or hopper, of which the face-plate 7 forms a part, tends to throw and hold the material toward the back plate. The face-plate 7 is provided with a shoulder 9 to receive the grinding-shell 6. This shell is of considerably less diameter than the internal diameter of the casing 5, so that an annular space 10 remains within the casing all the way around the cylindrical shell 6, said space opening into the enlarged space 11, a part thereof, in the bottom of the casing or housing. The grinding-ring 6 is held in place by the face-plate 7, which latter is secured by two pins 13, passing through lugs 14 on the exterior of the casing and secured by wedge-pins 15. As the face-plate is drawn into place the ring is firmly held between the face-plate 7 and an annular rib or face 16, that is turned up on the inside of the back of the housing. This rib is the only finished part upon the back of the housing, and the only other parts of the housing that are finished are the edges of the opening that receives the face-plate and that part just around the shaft in the back. The grinding-ring 6 appears to be made up of a series of short square rods set upon their corners. This, however, is not the case. The parts having this appearance

are preferably substantially rectangular bar projections 17, extending from a solid part of the ring 18, which part is cut down to the middle of the rectangular portions, so that even the solid portion of the ring presents a series of sharp-cornered corrugations, which are continued in the projections, between which there are longitudinal slots through which the fine material may escape into the space 10 around the ring. This ring 6 I always prefer to make in a single casting, and breakage thereof is extremely unlikely, because of the manner of holding the ring in the face-plate and between the same and the back of the casing. The beaters occupy almost all of the space within the shell 6 when the beaters are in motion, and it will be noted that the beaters first strike the material that enters through the hopper and while the material is upon the solid part of the ring 6. The material is thus crushed quite perfectly before it gets over onto the more slender parts of the shell or grinding-ring and contains no lumps or pieces that would be apt to cause breakage of the fingers or projections making up the slotted portion of the grinding-ring. The beaters rotate at a very high speed and set up centrifugal action both in the material and the air that enters at the hopper, also rotating the whole body of air very rapidly. The fine material and the coarse material whirl with the beaters and the air, and the coarse particles bound upon the inclined faces of the ring and are thus kept within the same, while the lighter particles have their force and weight overcome by the volume of air which presses out through the slots of the ring and thence down into the collector-box. It is because only the lighter particles are influenced by the air-currents that I am enabled to make slots between the fingers of the ring that are very large in proportion to the material that passes through them, and these slots being large will not readily clog. The beater is made up of a series of arms projecting from the shaft and having large heads that revolve close to the grinding-surface. These arms 20 are short steel bars swinging from or pivoted upon the shaft-head. This structure comprises a series of collars 21, arranged on the end of the shaft and carrying a number of longitudinal pins 22, the collars and said pins being held by a lock-nut 23, the thread of which turns oppositely to the direction of rotation of the shaft 4. There are grooves between the collars to receive the ends of the arms 20, and said arms are pivoted upon the pins 22. Any desired number of arms may be employed around each collar so long as all of them together constitute a perfectly-balanced head or beater upon the shaft. On the question of balancing the beater it may be observed that all of these parts are machine-finished and that the arms 20 may be made and weighed, so that they will be exactly alike

to the ounce, greatly facilitating the interchangeability of parts. It is obvious that the arms will be projected radially from the shaft by centrifugal force as said shaft rotates. The arms are comparatively light, and the necessary weight and the finish for the ends thereof are supplied by the interchangeable beater heads or hammers 24. These are preferably in the form of truncated pyramids. They are of such shape and size that they may be made exactly alike by familiar processes of casting or forging. Each has a square hole 25, flaring at the outer end, as shown at 26, Figs. 2 and 5, and these heads are slipped onto the arms 20 before the arms are fastened by the pins 21. The ends of the arms 20 are upset (see 27 27) to hold the heads or hammers 24, and said heads are projected out by centrifugal force when the shaft rotates. The heads may be and usually are quite loose upon the arms, and when all have been worn upon one corner the arms may be either taken out of the shaft and turned around or the heads may be turned around on the arms so as to present their sharp corners to the grinding-surface and the material when the machine is next used. These machines are often employed where different kinds of material are ground from day to day, and it is sometimes desirable to furnish heads that have but one sharp corner, the other being blunted or beveled to crush rather than break material of certain kinds. Further, the blunthammers have a tendency to crowd coarser material between the fingers or projections of the grinding-ring, and by using the same a coarser granulation may be secured with the machine without changing from a fine shell to a coarser one—that is, one having fewer fingers or projections and larger slots or smaller fingers. If the operator wishes to change the shell, he may do so very easily upon simply taking off the face-plate and without disturbing any other part of the machine. The beater-shaft operates at a very high speed, and hence I prefer to use two large bearings 3 3 with the driving-pulley 27 between them, and, furthermore, these bearings are made self-oiling by means of the endless chains 28, that hang down into the oil-chamber 29, that is formed within the base 2. The oil-chamber is preferably common to both bearings and has but one filling-pipe 30. As the fine product of the mill or disintegrator is discharged into the space 10 in the casing it is practically in suspension in the rapidly-moving currents of air which are driven down through the opening 11 through a hole 31 in the top of the collector box or bin 32. The fine material settles in this box, while the air escapes through a large area of fine cloth that is stretched upon the zigzag frames 33, which are placed over a hole in the top of the box 32. When enough material has been ground, the cloth collector is cleaned by knocking upon it and is then removed to be more thoroughly cleaned before it is again

used upon a different material, which often occurs in the preparation of drugs. The end 34 of the box is removed and the material taken out.

5 The advantages of my machine are its great capacity, its light weight considered in view of capacity, its cheapness both in original cost and in alterations or repairs, the small power required to operate the machine, and 10 the fact that the machine is practically unbreakable, owing to the construction and arrangement of the grinding-ring and the pivotal, and hence yielding, connections of the beater-arms to the shaft.

15 Having thus described my invention, I claim as new and desire to secure by Letters Patent—

1. In a machine of the class described, the combination of the casing provided with an 20 annular opening, with the face-plate arranged in said opening and provided with a shoulder 9 of less diameter than said opening, a spout provided in said face-plate for the admission of air and the material to be ground, the grinding-ring 6 situated in said shoulder 9 and extending to the opposite wall of the casing; the portion of said ring within the shoulder 9 being an internally-corrugated ring and the portion of the ring lying between the face-plate 25 30 and said rear wall being composed of regularly-spaced fingers, the openings between which lead into said casing, said casing having a suitable opening for the discharge of air and ground material and a suitable beater 35 revoluble within said grinding-ring, substantially as described.

2. In a machine of the class described, the combination of the casing provided with a chamber or space 10 11, with the grinding- 40 ring of substantially the same diameter throughout provided in said casing and of greater width than said space 10 11 and extending across the same, the portion of said ring extending across said space being composed of regularly-spaced fingers 17, the openings 45 between which communicate with said space, the remainder of said ring being internally corrugated, the rotary beater of substantially the same width as said ring and a feed-spout 8 whereby the material to be 50 ground is discharged upon the solid corrugated portion of said ring, substantially as and for the purpose specified.

3. In a machine of the class described, the 55 combination with the casing containing a grinding-ring of less diameter than the casing, said casing having a space or chamber 10 11 surrounding said ring, the rotary beater comprising the shaft 4, the collars 21 keyed 60 upon said shaft, the pins 22 extending through all said collars, the beater-arms secured upon said pins between said collars and the locking-nut 23 securing said pins and collars, substantially as described.

65 4. In a machine of the class described, the combination of the casing containing the

chamber 10 11 substantially semicircular at the top and straight at the bottom and provided at the bottom with a discharge-opening, with the face-plate provided with a spout 8 70 and having a shoulder 9 of less diameter than said casing, the internally-corrugated ring 6 situated in said shoulder 9 and having regularly-spaced fingers projecting across said chamber 10 11 and the rotary beater provided 75 within said casing and ring and of substantially the width of said ring, as and for the purpose specified.

5. In a machine of the class described, the combination of the casing 5, 5' with the face-plate filling an annular opening in the side of said casing and provided with a shoulder 9 of less diameter than said opening, means for securing said face-plate to the casing, a suitable spout in said face-plate, the grinding-ring situated in said shoulder 9 in the face-plate and held between the same and the rear wall of said casing, said ring being composed of a solid corrugated portion lying within said face-plate and being completed 90 by regularly-spaced rectangular fingers having discharge-slots between them, the shaft 4 extending into said casing and the rotary beater provided upon said shaft and having parts operating within the solid portion of said 95 ring, substantially as described.

6. In a machine of the class described, the base 2 and the bearings 3, 3 thereon, the vertical casing provided upon the end of said base and containing the chamber or space 100 10 11, in combination with the shaft 4 arranged in said bearings and extending into said casing, the beaters provided upon said shaft within said casing, the face-plate provided in the forward side or wall of said casing and containing an annular shoulder of less diameter than said casing, the grinding-ring seated in said shoulder, held between said face-plate and the rear wall of said casing and composed of regularly-spaced fingers 110 117 connected by a web or ring portion coextensive with said shoulder 9, and said face-plate having a suitable feed opening or spout, substantially as described.

7. A new article of manufacture comprising the grinding-ring consisting of the solid ring 6 having internal corrugations and the regularly-spaced fingers 17 of rectangular cross-section and constituting continuations of the internal corrugations of said ring, substantially as described.

8. A new article of manufacture, comprising the grinding-ring described, consisting of the solid ring portion 6 having internal longitudinal corrugations and the longitudinally-arranged regularly-spaced fingers 17 forming a perforated ring portion, said solid and perforated portion being of substantially the same diameter; substantially as described.

9. In a machine of the class described, the 130 casing proper provided with a large opening in one side, the beater-shaft entering through

the other side of the casing, the face-plate provided with a feed-spout, closing the opening in said casing and concealing the end of said shaft, the perforated grinding-ring provided in said face-plate and extending across the casing, and a suitable beater provided on the end of the shaft within the casing; substantially as described.

In testimony whereof I have hereunto set my hand this 5th day of May, 1900, at Minneapolis, Minnesota.

JOSEPH M. SCHUTZ.

In presence of—
C. G. HAWLEY,
M. E. GOOLEY.
